UNITED STATES PATENT OFFICE.

ALBERT J. KUEHN, OF DELHI, OHIO.

WATER-MOTOR.

SPECIFICATION forming part of Letters Patent No. 425,806, dated April 15, 1890.

Application filed March 15, 1889. Serial No. 303,452. (No model.)

To all whom it may concern:

Be it known that I, ALBERT J. KUEHN, a citizen of the United States, residing at Delhi, in the county of Hamilton and State of Ohio, have invented certain new and useful Improvements in Water-Motors, of which the following is a specification.

My invention relates to hydraulic motors of that class in which an endless revolving belt or chain is employed in connection with a series of brackets or buckets which are suitably attached to said belt or chain, and which brackets or buckets are carried down by water falling upon them. By this means the endless belt is constantly kept in motion, and passing over a drum imparts a rotary motion to said drum, which is transmitted to any kind of machinery by suitable gearing mechanism.

My improvements consist in constructing the body of the motor in such a manner as to dispense with the use of screws, nails, and the like, making what I may term a "knockdown" flume or penstock.

They further consist in the employment of an auxiliary flume or penstock, which may be elevated in case backwater is present, thus not interrupting the working of the motor.

They further consist in the peculiar construction of the endless belt and the brackets or buckets on which the water falls.

In the accompanying drawings, forming part of this specification, Figure 1 is a side view of my improved water-motor. Fig. 2 is a longitudinal section of the motor shown in Fig. 1, the parts, however, being made to assume the position taken by them when the auxiliary flume is elevated to avoid backwater. Fig. 3 is a front view of part of the endless belt and showing the manner of connecting the brackets to it. Fig. 4 is a view of a modified form of the endless belt, a rope being employed; and Fig. 5 is a view of part of one of the wooden sides of the flume or penstock, showing the manner in which the front and back pieces are connected thereto. Fig. 6 is a perspective view of my improved water-motor.

The side pieces A of the flume or penstock are preferably made of wood, and of the shape shown in Fig. 5, with creased or rabbeted edges, into which creases the turned edges of the front and back pieces A' fit snugly

and tightly. These front and back pieces are preferably made of galvanized iron. At the bottom these side pieces A and the back piece A' are fastened together by band-piece A², which passes around them and is fastened at its edges by fitting into the creases in the edges of the side pieces A. This band-piece A² is fastened to the foundation A³ of the device in any suitable manner. At the top the side pieces A and the front and back pieces A' are held together by a cap-piece B slipped over and around them. The forebay B' is made of any preferred shape, and is connected to the cap-piece B in any suitable manner. I may when desired form the cap-piece B and the forebay B' of one and the same piece. The cap-piece B, forebay B', and band-piece A² are made of any suitable material, preferably of galvanized iron. Near the middle of the flume I slip on the center band-piece B², made preferably of galvanized iron. It will be seen that the side, front, and back pieces and the various band-pieces and the forebay can be easily taken apart and shipped, and easily and quickly set up, making this part a "knockdown" device. If desired, I may bolt these various parts together, preferring, however, to connect them as specified.

The forebay has extending from it two arms C, to which I suitably connect two supporting-bars C'. These bars may be of any peculiar shape and size, and connected together in any suitable manner. At the bottom these bars are preferably connected to the ears C². In these supporting-bars C', near the top, is suitably journaled on a shaft C³ the drum D. In the ears C² is suitably journaled a small friction-roller D'.

The supporting-piece D² passes under the cap-piece B, down under the center band-piece B², then up behind the roller D', as shown in Fig. 2, where it is formed or split into three pieces—that is to say, into the center piece E and side pieces E'. The side pieces E' are bent around the shaft on which the friction-roller is connected, (see dotted lines, Fig. 2,) and consequently support the friction-roller D', so that it need not be journaled in the pieces C', and is therefore at all times free to be pressed outward by exerting pressure on the supporting-piece D² (which supporting-

piece carries at its upper end the roller D' through the agency of the projection W² of the lever W'. When pressure is removed, the spring-support D² and roller will again assume their normal position.

The endless belt F is preferably made of galvanized iron. At proper intervals on said belt are connected the brackets or buckets F' in any suitable manner; preferably, however, the belt F is passed through slots F² (see Fig. 3) in the back piece F³ of the bracket F'. When desired, I may pass the ferrules G around said back piece F³ of the brackets, to keep the belt F from slipping and to strengthen the bracket. The top piece G' of the bracket F' is also preferably formed as shown, and is hinged in any suitable manner to the back piece F³, preferably by a flexible hinge a. The piece F³ is prevented from dropping or falling down by the bracket-arm H, formed as shown, and is connected in any suitable manner to the top piece G'. A flat spring H', connected in any suitable manner to the back piece F³, holds the top piece G' in proper position. Instead of the belt, I may use ropes H², (see Fig. 4,) which are passed through slots, as shown in Fig. 4.

The belt F passes over the drum D, suitably journaled, as shown, and in the present instance under two drums K K', as shown. It may, however, pass under only one drum. By passing the belt under one drum and using the concave K² a perfect motor would be formed—that is, using the same in connection with the parts heretofore set forth; and when used for domestic purposes, as running a small engine, dynamo, or the like, where the water is provided from a water-main or the like, this is all I use or need use.

The remainder of the device is peculiarly formed to make it operative in case backwater is present where the flume or penstock is located. I shall now describe said mechanism.

I provide a guide-piece L on each side of the device, cut away at L' to form a bearing-surface for the journal of the drum K' when not elevated. (See Fig. 1.) I also provide an auxiliary flume or frame M, formed, as shown, of front piece M', back piece M², which are connected by side pieces M³, which can be seen in Fig. 1 through the slot N. This sliding frame or auxiliary flume M is also preferably provided with L² and a spout L³.

To the shaft N², which carries the drum K', I connect one end of an arm N³, the other end of which is connected to the shaft which supports the drum K. At P, I connect to the frame-work one end of an arm P', connected at its other end to a roller-shaft P². From this shaft P² to the shaft which carries the drum K extends the arm P³. These arms and shafts connect the drums and support them, and are loosely connected at their various points of connection.

R represents a supporting-piece formed of one piece of metal. At R' it is hooked over

the cap-piece B. It then extends downward under the cap-piece, and then is bent outward to form an elongated eye R², in which 70 fits a pin R³. (See Fig. 2.) It then passes downward under the center piece B², and then upward, forming the lap R⁴. This piece is therefore formed and connected without the use of nails, &c. The pull-lever S is journaled in the pin R³ in any suitable manner.

To the extension S² of the lever S, I attach one end of a rod S³, the other end of said rod being connected to the sliding piece M at T. (See Fig. 1.) The rod S³ passes through an 80 eye T', which supports and guides said rod. This construction and the arms, &c., for holding and supporting the drums are similar on both sides of the flume, except that there is only one handle to the lever S. When the 85 lever S is pulled backward, it raises the extensions S², and the rods S³ being attached thereto, said rods are elevated or pulled upward in the slot N, and the lower ends of said rods, being rigidly attached to the sliding frame or auxiliary flume M, pull it upward in their movement. When the sliding frame M moves upward, the drums K and K', being journaled therein, move upward with it, and the arms N², P², and P' are forced outward, 95 forcing the drum K, and consequently the belt F, outward, and the parts are made to assume the position given them in Fig. 2, thus escaping the backwater. When it is desired to lower this mechanism just described, the lever S is pushed back into its normal position and the parts are lowered.

When the belt F becomes slack, I tighten it in the following manner: In the lower end of the supporting-arms C, I hang the friction-roller D', heretofore referred to. I also provide a peculiarly-shaped hand-lever W', (see Fig. 1,) which passes through the ears C² and is journaled therein. It is bent upward, as shown at W² in Fig. 2. When the belt is 100 slack, the lever W' is pulled upward and forward, thus bringing the projection W² of the lever against the spring supporting-piece D², carrying at its upper end the roller D', thus forcing said roller against the belt, forcing 115 the belt outward slightly, thus making it taut. When the lever is brought back, the roller is brought back off the belt as the pressure in the spring supporting-piece D², which carries said roller, is removed, and it finds its normal 120 position.

A side view of the lever W' is shown in Fig. 1. It is journaled in the supporting-pieces C², passing through said supporting-pieces. Between said supporting-pieces it is 125 bent upward at an angle to form the projection W², (see Fig. 2;) consequently when the lever is moved upward the projection W² will move downward and outward and against the spring supporting-piece D².

The operation is very simple and can be readily understood from the foregoing description. The water passes into the fore-bay B', passing thence into the flume or pen-

stock, and in passing into said flume the water falls upon the brackets or buckets F, and said buckets fitting tightly and snugly in said flume they are forced downward, imparting motion to the belt F, and said belt passing over drum D imparts a rotary motion to said drum, which motion is transmitted by suitable gearing to any kind of machinery to be operated. The brackets being hinged, as shown, should any obstruction pass by chance into the flume they will "give" and allow the obstruction to pass. When backwater is present, the auxiliary flume M may be raised, as before specified. When raised, the device appears as shown in Fig. 2. Other means than those herein specified may be employed in raising and lowering said auxiliary flume, and I may also slightly alter the other constructions. The drums, when a metal belt is used, are preferably covered with rubber or leather or similar substance. The drum K is preferably slightly weighted, so that it will fall outward more readily when elevated.

What I claim as new and of my invention, and desire to secure by Letters Patent, is—

25

1. In a water-motor, a flume, brackets, and drums, in combination with a belt, as F, made of galvanized iron, passing through slots in the brackets, substantially as set forth.

2. In a water-motor, a flume composed of 30 wooden sides, creased to receive the flanges on the front and back pieces, and drums D and K', over which passes belt F, having the peculiar-shaped brackets F', said belt F passing through slots in said brackets, as shown, 35 substantially as set forth.

3. In a water-motor, a flume, in combination with an auxiliary sliding flume or frame, drums K and K', drum D, drums K and K' moving upward and downward with said auxiliary flume, and lever S, substantially as set forth.

40

ALBERT J. KUEHN.
